US00D796234S

(12) **United States Design Patent** (10) **Patent No.:** **US D796,234 S**
Thaler et al. (45) **Date of Patent:** **** Sep. 5, 2017**

(54) **DISPLAY STRUCTURE**

- (71) Applicant: **Apple Inc.**, Cupertino, CA (US)
- (72) Inventors: **Frank Craig Thaler**, Santa Cruz, CA (US); **Russell John Kaaihue Heirakuji**, Cupertino, CA (US); **Carly Lynn Marasco**, Los Gatos, CA (US)
- (73) Assignee: **Apple Inc.**, Cupertino, CA (US)
- (***) Term: **15 Years**
- (21) Appl. No.: **29/600,909**
- (22) Filed: **Apr. 17, 2017**

Related U.S. Application Data

- (63) Continuation of application No. 29/526,384, filed on May 8, 2015, now Pat. No. Des. 785,975, which is a continuation of application No. 29/507,089, filed on Oct. 23, 2014, now Pat. No. Des. 770,203.
- (51) **LOC (10) Cl.** **06-06**
- (52) **U.S. Cl.** **D6/675**

(57) **CLAIM**

The ornamental design for a display structure, as shown and described.

DESCRIPTION

FIG. 1 is a top front perspective view of a display structure showing the claimed design;

FIG. 2 is a top rear perspective view thereof;

FIG. 3 is a right side view thereof;

FIG. 4 is a left side view thereof;

FIG. 5 is a rear view thereof;

FIG. 6 is a front view thereof;

FIG. 7 is a top view thereof; and,

FIG. 8 is a bottom view thereof.

The broken lines in the figures show portions of the display structure that form no part of the claimed design.

1 Claim, 6 Drawing Sheets
